UNITED STATES PATENT OFFICE.

LOUIS CLÉMENCET, OF WEST HOBOKEN, NEW JERSEY, ASSIGNOR TO M. H. BIRGE & SONS, OF BUFFALO, NEW YORK.

DESIGN FOR WALL-PAPER.

SPECIFICATION forming part of Design No. 23,662, dated October 2, 1894.

Application filed August 27, 1894. Serial No. 521,463. Term of patent 3½ years.

To all whom it may concern:

Be it known that I, LOUIS CLÉMENCET, a citizen of France, residing at West Hoboken, in the county of Hudson and State of New Jersey, have invented and produced a new and original Design for Wall-Paper, of which the following is a specification.

The design consists of an arrangement of large branches of flowers and leaves of roses forming an all-over pattern over the paper as represented in the accompanying drawing. The border or upper portion of the design is also formed of branches of flowers and leaves of roses and small grass-like sprays which

alternate with small ornamental panels filled with lattice work with flowers and leaves of roses in the center of said panels, as shown in the drawing.

What I claim is—

The design for wall paper herein shown and described.

Witness my hand this 22d day of August, 1894.

LOUIS CLÉMENCET.
